Edwin S. Simons

UNITED STATES PATENT OFFICE.

EDWIN S. SIMONS, OF PHILADELPHIA, PENNSYLVANIA.

DESIGN FOR A THIMBLE.

SPECIFICATION forming part of Design No. 21,746, dated August 2, 1892.

Application filed July 2, 1892. Serial No. 438,827. Term of patent 3½ years.

To all whom it may concern:

Be it known that I, EDWIN S. SIMONS, a citizen of the United States, and a resident of the city and county of Philadelphia, and State 5 of Pennsylvania, have invented a new and original Design for Thimbles, of which the following is a specification.

My design is illustrated in the accompanying drawings, in which—

Figure 1 is a side elevation of a thimble having the design applied, and Fig. 2 is a diagrammatic view of the same, representing the surface spread out in a plane.

The essential feature of the design is the ornamental scroll pattern upon the base A, arranged adjacent to the upper and lower edges of the base with the intermediate portion B

unornamented. The upper pattern consists of the scrolls *aa* in oppositely-arranged pairs with the intermediate projecting foliate parts *b*, and the lower pattern consists of the oppositely - arranged ornamental scrolls *c*. The crown C of the thimble has a roughened or stippled surface.

What I claim as new, and desire to secure 25 by Letters Patent, is—

The design for a thimble, substantially as shown in the accompanying drawings.

In testimony of which invention I have hereunto set my hand.

EDWIN S. SIMONS.
